SHOE FILLER

Odilon Boivin, Montreal, Quebec, Canada, assignor of fifty per cent to Joseph E. Tetreault, twenty-five per cent to Joseph E. Trepassey, and twenty-five per cent to Joseph E. Barrette, all of Montreal, Quebec, Canada

Application December 2, 1938, Serial No. 243,592

2 Claims. (Cl. 36—3)

The present invention relates to improvements in shoe filler construction.

An object of the invention is the provision of a shoe filler of generally improved construction.

Another object of the invention is the provision of a shoe filler which will retain its original condition for a long time.

A further object of the invention is the provision of a shoe filler having efficient insulating qualities.

Still another object of the invention is the provision of a shoe filler designed to provide efficient ventilating means in a shoe bottom.

A still further object of the invention is the provision of a shoe filler designed to provide channels in the ball section of a shoe bottom for air circulation and cooling.

Another object of the invention is the provision of a shoe filler of the aforesaid character which is strong, flexible and comfortable.

Other objects and advantages of the invention will become apparent as the description progresses.

In the accompanying drawing forming a part of this specification and in which like reference characters are employed to designate corresponding parts throughout the same:

Figure 1 is a top perspective view of the improved filler,

Figure 2 is a bottom plan view of the same, Figure 3 is a fragmentary enlarged transverse section through the filler in bent arrangement,

Figure 4 is an enlarged fragmentary section taken on the line 4—4 of Figure 2, and

Figure 5 is a side elevational view of a shoe equipped with the improved filler partly broken away to illustrate the interior construction.

Referring to the drawing, wherein for the purpose of illustration is shown a preferred embodiment of the invention, 10 generally designates a sheet body member formed of strong, flexible material, such as leather. On the inner or bottom surface of the member 10 are formed a plurality of, in the present instance four, transversely extending ribs 11 projecting from the inner face and of a thickness substantially corresponding to the thickness of the body 10. As shown to advantage at Figure 4, these ribs extend across the ball portion of the member 10 and are spaced apart to form channels 12 of a width substantially exceeding that of the ribs.

To the inner or bottom surface of the member 10 is secured a complementary bottom layer C, constituting a relatively thick layer of cork, applied to cover the undersurface of the body sec-

tion with the exception of the projecting ribs 11. This bottom layer, which may be of uniform thickness throughout, is preferably applied to form a rear section 14 extending from the rear-most rib 11 to the rear edge of the heel, covering the shank and heel portions, as shown at Figure 2. At the forward portion of the filler is provided a front section 15 extending from the foremost rib 11 to the front edge of the toe. Intermediate sections, in the forms of straight 10 elongated strips 16, are fitted and secured in the channels 12 formed between the respective ribs 11. Inasmuch as the bottom layer C of the composite assembly is preferably of a thickness substantially exceeding that of the ribs 11, the formation hereinbefore described provides grooves 17 therein, corresponding to the width of the ribs and extending the full width of the layers. In the bottom exposed surface of the layer C is also formed a groove 18 extending in an approximately longitudinal direction across and intersecting the transverse grooves 17, although actually the groove 18 may extend in a straight line at an angular inclination to the longitudinal line of the article. At its ends, which terminate forward and rearward of the transverse grooves 17, the longitudinal groove 18 communicates with a pair of apertures 19 through the two face to face layers, providing vent openings.

When assembled in a shoe bottom, as illustrated at Figure 5, the two-layer filler is accurately fitted within the cavity in the outline of the rib of an insole, indicated at I, that is, between the central area of the insole and the outsole O. For such assembly, the insole I is preferably provided with holes H formed in correspondence with the vent apertures 19 in the filler, so that air may properly circulate through the main longitudinal groove 18 and the cross grooves 17. This enables very efficient air circulation and cooling of the shoe bottom, particularly at the ball of the foot, and at the same time enables convenient flexing thereto, as indicated at Figure 3. Furthermore, the present filler will not flatten or curl but will maintain an even top surface free from depressions or wrinkles and, due to its structure and assembly, in the cavity of an insole, will remain properly in place at all times. The grooves in the filler impart great flexibility thereto while its insulating qualities provide a shoe sole which is relatively cool in summer and warm in winter.

It is to be understood that the form of my invention herein shown and described is to be taken as a preferred example of the same, and

that various changes as to the shape, size and arrangement of parts may be resorted to without departing from the spirit of the invention or the scope of the subjoined claims.

5 Having thus described my invention, I claim:

1. A shoe filler comprising a top leather layer having a pair of vent apertures therein and formed on its inner surface with a plurality of transversely extending ribs, and a bottom layer 10 of cork secured in face to face relation with the inner side of the other layer and covering the underside of the latter with the exception of the ribs to form transverse grooves in the said cork layer, the bottom face of the cork layer being 15 formed with a groove intersecting the said transverse grooves and communicating with the vent apertures in the top layer.

2. A shoe filler comprising a top leather layer having a pair of vent apertures formed therein in the ball and toe portions, a plurality of spaced transversely extending ribs of thickness substantially corresponding to that of the top layer and 5 on the inner face thereof substantially within the area limited by the vent apertures, and a bottom layer of cork secured in face to face relation with the inner side of the leather layer and thicker than the transverse ribs, said ribs being 10 uncovered by cork to form transverse grooves in the cork layer of a depth less than the cork thickness, the bottom cork layer being furthermore provided with a groove intersecting the transverse grooves and ending at each end in 15 one of the vent apertures of the leather layer.

ODILON BOIVIN.
